UNITED STATES PATENT OFFICE.

EDWIN LUNDGREN, OF FREDERICK, MARYLAND, ASSIGNOR TO INTERNATIONAL COMBUSTION ENGINEERING CORPORATION, OF NEW YORK, N. Y., A CORPORATION OF DELAWARE.

FURNACE-WALL STRUCTURE.

Application filed September 22, 1925. Serial No. 57,811.

My invention relates to stokers and has special reference to the construction of the walls of the fire box or chamber of stokers of the underfeed type.

5 The principal object of the invention is to provide novel and improved means for preventing the formation of clinkers on the side and bridge walls of stokers, especially underfeed stokers in which the underfeed method 10 of feeding and burning the coal tends to produce an adhering effect on refractory surfaces between the clinkers and ashes.

Another object of the invention is to provide a novel and improved wall structure for 15 the fire box of a stoker.

The several features of the invention, whereby the above-mentioned and other objects may be attained, will be clearly understood from the following description and 20 accompanying drawings, in which:

Figure 1 is a longitudinal sectional view of an underfeed stoker embodying the features of the invention in their preferred form;

25 Fig. 2 is a detail sectional view, on an enlarged scale, taken on the line 2—2 of Fig. 3;

Fig. 3 is a detail sectional plan view on an enlarged scale, taken substantially on the line 2—2 of Fig. 1; and

30 Figs. 4, 5 and 6 are detail views in perspective of component parts of my improved structure.

The underfeed stoker illustrated in the drawings is provided with a fire box or chamber 2, an underfeed grate section 4 comprising a plurality of downwardly and rearwardly inclined retorts and tuyère structures alternately arranged, an ash pit 6, a dump grate 7 extending across the ash pit, and a wind box 8 located beneath the retorts and tuyère structures to which air is supplied under pressure through a conduit 10 which is controlled by dampers 12. The fire box or chamber 2 is provided with side walls 14, a front wall 16 and a rear or bridge wall 18.

45 In underfeed stokers, because of the method of feeding and burning the coal, considerable difficulty has been experienced by the formation of clinkers on the side and bridge walls of the fire box or chamber. In the illustrated construction novel and improved means is provided for overcoming this difficulty, and while such means is shown in the drawings as

associated with merely the bridge wall it will be apparent that similar means may be associated with the side walls of the furnace. As shown, the bridge wall is provided with an inwardly opening channel 20 extending between the side walls and horizontally arranged. The side walls are provided with cylindrical 55 openings 22 that are provided with sleeve linings 23 and are arranged in alinement with said channel. A water spray pipe 24 extends through said openings 22 and through the channel, and is provided with a series of apertures 26 for spraying the water into the ash pit of the furnace at a point in proximity to and slightly above the rear edge of the dump grate 7. Each end of the spray pipe 24 is connected by a union 28 with a pipe 30 which in turn is in communication with a branch pipe 32 connected with a suitable source of water supply, a branch pipe 34 connected with a suitable source of steam supply, and a blow-off pipe 36 which is arranged in alinement 70 with the pipe 30, the pipes 32, 34 and 36 being controlled by valves 37. The portion of the spray pipe 24 arranged within the channel 20 is encompassed by a housing 38 fitted within the channel and having the inner face of its inner wall 40 in substantially the plane of the inner side of the bridge wall. This housing 38 is made in a plurality of sections arranged end to end (Fig. 4). Each section of the housing is provided with a plurality of strengthening 75 partitions 41 extending transversely thereof, and has its forward wall provided with a rectangular opening 42 extending between each two adjacent partitions, spaced a distance below the upper edge thereof, and through 80 which fluid discharged from the spray pipe 24 may be directed into the ash pit. The several sections of the housing 38 have their forward portions supported upon a face plate 44 which is inserted in the bridge wall and has its front side arranged flush with the inner side of the front sides of the housing and bridge wall. The face plate 44 is made in sections arranged end to end and corresponding in 85 length and arrangement to the sections of the housing 38. The under side of each section of the housing is provided with a series of four depending lugs 46 which are arranged back of a shoulder 48 formed on each section of the face plate. Each section of the face plate is further provided with a rearward ex- 90 95 100 105

tension 50 having a longitudinally extending depending lug 52 on its rear edge. The rear portion of the several sections of the housing 38 is provided with depending lugs 53 that are supported by a horizontally arranged plate 54 inserted in the bridge wall. The supporting plate 54 is made in sections arranged end to end and corresponding in length and arrangement to the several sections of the housing 38 and the face plate 44. The forward edge of each section of the supporting plate 54 is provided adjacent its ends, with forwardly projecting lugs 56 that are spaced a distance below the top of the plate and have upwardly turned ends 57 which cooperate with the lug 52 to hold the face plate 44 in position. With this construction, upon water being admitted to the spray pipe 24 from the valve controlled water supply pipe 32, the water discharged through the perforations 26 will be sprayed through the several openings 42 and into the ash pit. Such spraying of the ashes will maintain them moist and cool and thus will effectively prevent clinkers from forming on the lower portion of the bridge wall. Also, as the spraying device is located in proximity to the rear edge portion of the dump grate 7, the latter will be protected from overheating. As the spray pipe 24 is spaced a considerable distance from the outlet ends of the openings 42 it will be apparent that there is very little, if any, danger of the perforations 26 becoming clogged.

By closing the valve of the water supply pipes 32 and opening one of the steam pipes 34 and the valve of the opposite blow-off pipe 36, steam may be admitted to blow out the pipe and the spraying aperture 26 in the pipe.

The lining sleeves 23 of the openings 22 are of sufficient diameter to permit the spray pipe 24, when the unions 28 are disconnected, to be slipped bodily out of the lining sleeves and the channel 12. When the pipe 24 has been removed, the several sections of the face plate 44 may be removed upon breaking away slightly a part of the masonry of the bridge wall, and as the face plate holds the sections of the housing in place these sections may then be removed.

As will be evident to those skilled in the art, my invention permits various modifications without departing from the spirit thereof or the scope of the appended claims.

What I claim is:

1. A furnace chamber having at least one of its walls provided with an inwardly opening channel horizontally arranged and at least one of the two adjacent walls provided with an opening in alinement with said channel, a spray pipe extending through said opening and channel and removable therefrom; a housing enclosing said pipe, made in sections and inserted in said channel, each section having a longitudinally extending opening in its inner wall spaced a distance

from the upper edge thereof, and a face plate removably inserted in said wall directly beneath said housing and forming a part of the inner side of said wall, said face plate and housing sections having engaging portions for detachably holding the housing in place. 70

2. A furnace chamber having at least one of its walls provided with an inwardly opening channel horizontally arranged, and at least one of the two adjacent walls provided with an opening in alinement with said channel, a spray pipe extending through said opening and channel and removable therefrom, a housing made in sections arranged end to end and enclosing said spray pipe, 80 each section having an opening through which fluid discharged from said pipe may be directed, a face plate inserted in said wall directly beneath the sections of said housing, each section of said housing having depending lugs and said face plate having cooperating lugs for locking said housing in place, and a second plate having its forward portion arranged beneath said housing and having portions cooperating with portions of said face plate for locking said face plate in place. 85

3. A furnace chamber having at least one of its walls provided with an inwardly opening horizontal channel and the two adjacent walls provided with openings in alinement with said channel, a spray pipe extending through said openings and channel and removable therefrom, a housing enclosing said spray pipe having the inner side of its inner 100 wall substantially in the plane of the inner side of said channeled wall, said housing being made in sections arranged end to end, each section having a plurality of openings in its inner wall spaced from the upper edge 105 thereof through which fluid discharged from said spray pipe may be directed, a face plate inserted in said wall beneath said housing having its inner side substantially in the plane of the inner side of the inner wall of 110 said housing, and having an inward projection extending beneath said housing, the sections of said housing and said face plate having cooperating lugs for locking the sections of the housing in position, and a supporting plate extending beneath the rear portion of 115 said housing and inserted in said chamber wall for supporting the rear portion of the sections of said housing, said rearward projection of said face plate and said supporting plate having cooperating lugs for locking said face plate in position. 120

4. A furnace chamber having at least one of its walls provided with an inwardly opening channel horizontally arranged, a spray pipe extending through said channel and removable therefrom, a housing made in sections arranged end to end and enclosing said spray pipe, each section having an opening through which fluid discharged from said 125

pipe may be directed, a face plate inserted in
said wall directly beneath the sections of said
housing, each section of said housing and
said face plate having engaging portions for
holding said housing in place, and a second
5 plate having its forward portion arranged
beneath said housing, and having portions

cooperating with portions of said face plate
to hold said face plate in place.

In testimony whereof, I have signed my ¹⁰ name to this specification this 21st day of September, 1925.

EDWIN LUNDGREN.
